Inventor:
Hyman Charm,
by Walter E. Lombard,
Atty.

UNITED STATES PATENT OFFICE.

HYMAN CHARM, OF DORCHESTER, MASSACHUSETTS.

SUPPORT FOR OUTLET BOXES.

Application filed February 20, 1922. Serial No. 537,735.

To all whom it may concern:

Be it known that I, HYMAN CHARM, a citizen of the United States of America, and a resident of Dorchester, in the county of 5 Suffolk and State of Massachusetts, have invented certain new and useful Improvements in Supports for Outlet Boxes, of which the following is a specification.

This invention relates to devices for supporting outlet boxes of electric lighting fixtures, and has for its object the provision of a simple device which may be inserted readily through an opening in the ceiling and then adjusted to prevent displacement there- 15 of when the outlet box has been secured in position thereon.

The invention consists of a threaded tubular member having ears clamped thereto in adjusted position, which ears are adapted to 20 support L-shaped arms, the longer arms of which are adapted to be disposed parallel with said member when being inserted in the opening in the ceiling and subsequently to be disposed perpendicular to said member and rest on the laths of the ceiling.

The invention further consists in certain novel features of construction and arrangement of parts which will be understood readily by reference to the description of 30 the drawings and to the claims to be herein-after given.

For the purpose of illustrating the invention, one preferred form thereof is shown in the drawings, this form having been 35 found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

45 Fig. 1, represents a vertical section of a support embodying the principles of the present invention, shown supporting an outlet box on a ceiling.

Fig. 2, represents a plan of the support, 50 and

Fig. 3, represents an elevation of the same.

Similar characters indicate like parts throughout the several figures of the drawing.

In the drawings 10 is an outlet box of usual construction which it is desired to clamp in position against a ceiling 11, and 60 12 is an enclosing casing which may be of any design.

In the ceiling 11 is formed an opening 13 through which the electric wires are fed to the outlet box 10 and from this box to the lamps supported in any well known manner from the casing 12. This outlet box 10 is 65 provided with a central opening 14 through which the threaded tubular member 15 extends, this member having on its lower ends the nuts 16, 17 by which the outlet box 10 may be clamped to the ceiling 11 when the 70 upper end of said tubular member has been properly positioned. This positioning of the member 15 is accomplished in the following manner.

Two straps 18 are provided each having 75 midway of their length a curved portion 19 the inner face of which is provided with a thread to engage the thread of the tubular member 15.

The outer ends of these straps 18 form 80 ears 20, 21 the former having a greater thickness than the latter.

Through each ear 21 extends a clamping screw 22 the shank of which is threaded into the ear 20.

These ears 20 and 21 are separated from 85 each other as shown in Fig. 2 when the straps 18 have been clamped to the member 15.

Between these ears 20, 21 and between 90 said member 15 and the shank of the screws 22 are loosely disposed the flat sided L-shaped ends 23 of the arms 24.

These arms may be moved about the 95 screws 22 into positions parallel and adjacent to the member 15 and when in this position they may be easily inserted through the opening 13 in the ceiling 11 and then moved into position perpendicular to said member 15 as indicated in Fig. 1, in which 100 position they will rest upon the laths 25 of the ceiling 11.

The arms 24 cannot be moved beyond a perpendicular to the member 15 owing to the ends 23 bearing against said member 15 105 as is perfectly obvious.

When thus disposed the outlet box 10 may be positioned on the lower end of the member 15 and clamped to the ceiling by the nuts 16, 17.

One difficulty found to exist in supports now in general use is that the supporting member for the outlet box is not adjustable and consequently in some cases the lower 5 end projects too far and in other cases not far enough to accommodate itself to various forms of outlet boxes and different thicknesses of ceilings.

This objection is wholly overcome in the 10 device herein shown and described for by adjusting the screws 22 the pressure of the straps 18 upon the member 15 may be relieved and then the member 15 may be adjusted relatively to said straps 18 to any 15 desired degree and the adjustment having been made, the screws 22 are again turned sufficiently to rigidly clamp the straps 18 to said member 15 and prevent further rotation thereof holding the same in adjusted 20 position while the nuts 16, 17 are being positioned on the lower end of said member 15.

The adjustment of the member 15 relatively to the straps 18 may be made readily after the arms 24 are in the positions shown 25 in Fig. 1 by first tilting the device in one direction and then in the opposite direction to permit the oppositely disposed screws 22 being turned by a screw driver inserted from beneath through the opening 13 in the ceiling 30 ing 10.

This makes a very simple but most effective device for supporting outlet boxes which may be adjusted to accommodate itself to various forms and styles of outlet 33 boxes and to varied thicknesses of ceilings.

It is believed that the operation and many advantages of the invention will be understood from the foregoing description.

Having thus described my invention, I 40 claim:

1. In a support for outlet boxes, a tubular member; a device adjustable thereon provided with oppositely disposed ears projecting laterally therefrom; L-shaped arms 45 mounted to move about pivots on said ears to cause one branch of each arm to bear against the periphery of said tubular member; and means for supporting an outlet box on the lower end of said member.

50 2. In a support for outlet boxes, a tubular member; a device thereon provided with two pairs of ears projecting laterally therefrom and oppositely disposed; a pin in each pair of ears; an arm having a flattened L-shaped end positioned between each pair of ears and between said member and the periphery of said pin; and means for support-

ing an outlet box on the lower end of said member.

3. In a support for outlet boxes, a tubular 60 member; two straps on opposite sides of said member; means for clamping said straps to said member; arms normally supported by but disconnected from said clamping means, the main portions of said arms being adapted to be moved from positions parallel to said member to positions perpendicular thereto; and means for supporting an outlet box on the lower end of said member.

4. In a support for outlet boxes, a tubular 70 threaded member; two straps on opposite sides of said member having threaded portions coacting with the thread of same member; means for clamping said straps to said member; arms normally supported by but 75 disconnected from said clamping means, the main portions of said arms being adapted to be moved from positions parallel to said member to positions perpendicular thereto; and means for supporting an outlet box 80 on the lower end of said member.

5. In a support for outlet boxes, a cylindrical member; straps adjustable relatively thereto and having oppositely disposed ears projecting laterally therefrom; 85 means for clamping to a ceiling an outlet box on the lower end of said member; clamping screws extending through said ears; and arms supported by but disconnected from said screws the main portions of 90 said arms being adapted to be moved from positions parallel to said member to positions perpendicular thereto.

6. In a support for outlet boxes, a cylindrical threaded member; straps provided 95 with threads coacting with the thread of said member and having oppositely disposed ears projecting laterally therefrom; means for clamping to a ceiling an outlet box on the lower end of said member; clamping screws extending through said ears; and arms supported by but disconnected from 100 said screws the main portions of said arms being adapted to be moved from positions parallel to said member to positions perpendicular thereto.

Signed by me at 746 Old South Bldg., Boston, Mass. this 16th day of February, 1922.

HYMAN CHARM.
